UNITED STATES PATENT OFFICE.

CORNELIUS J. NOLAN, OF TOLEDO, OHIO.

MACHINE FOR BLOWING HOLLOW GLASS ARTICLES.

No. 822,220.

Specification of Letters Patent.

Patented May 29, 1906.

Application filed October 29, 1904. Serial No. 230,566.

To all whom it may concern:

Be it known that I, CORNELIUS J. NOLAN, a citizen of the United States, residing at Toledo, in the county of Lucas and State of Ohio, have invented certain new and useful Improvements in Machines for Blowing Hollow Glass Articles, of which the following is a specification, reference being had therein to the accompanying drawings.

The invention consists in the construction of a glass-blowing machine, and relates particularly to machines designed for blowing hollow articles—such, for instance, as incandescent-lamp bulbs—although it may be used for other articles.

The invention consists in the construction, arrangement, and combination of the parts, as more fully hereinafter described, and particularly pointed out in the claims.

In the drawings, Figure 1 is a side elevation of my improved machine, a part of the framework and the tank being in section to more clearly illustrate the construction. Fig. 2 is a section on line *x x* of Fig. 1, showing the operating parts on the base in plane. Fig. 3 is a rear elevation, partly in section. Fig. 4 is a detail section illustrating the construction of the starting and stopping mechanism.

A is the base of the machine, in one side of which is the tank *B*, adapted to contain water for wetting the paste-lined molds between operations.

C is the arch-bracket on the base and sprung over the inner edge of the tank. In this bracket is supported a standard *C'*. To the standard are secured the brackets *D* and *D'*, which support and guide the blow-iron *E*. At the upper end of the post is a bracket *F*, in which is slidably secured a coupling *F'*. This coupling has secured to its upper end the pinion *G*, to which the air-supply pipe *G'* has a swiveled connection. This air-pipe connects with a passage *a* in the top of the post *C'*, which in turn connects with a passage *a'*, through a bracket or arm *H*, extending rearwardly from the post, and the passage in this arm connects with the air-supply under pressure from any suitable point, (not shown,) being through a valve *d'*. The pinion *G* meshes with a gear-wheel *I*, journaled on the upper end of the post, which in turn is driven by a gear-wheel *I'* on the upper end of the shaft *J*, motion being imparted to this shaft in the manner to be hereinafter described.

The pinion *G* being driven, the coupling *F'*

will likewise be rotated when the blow-iron is therein. It will be rotated either by a suitable connection for this purpose or in the well-known manner for such machines. For instance, I may use such a connection as shown in Patent No. 653,523. The coupling is reciprocated by the lever *J'*, pivoted on the bracket *J''* and having its end connected to the actuating-rod *K*, which extends down to the base of the machine, which is provided with a roller-wrist *c*, engaging a camway *d* in the cam-wheel *L*, secured to the shaft *M*. Secured to this wheel also is a bevel gear-wheel *e*, meshing with a bevel gear-wheel *f* on the shaft *J* for rotating the same.

The valve *d'* has a valve-rod *i*, which extends down to the cam-wheel *L*, and is provided with a roller *i'*, adapted to be actuated by the cam-flanges *k* and *k'* thereon to open and close the valve in the manner to be hereinafter described.

N is a motor on the base. *N'* is a pinion on its shaft, which meshes with a gear-wheel *O*, loosely sleeved on a shaft *O'*. Fixed to the shaft *O'* is a worm *P*, and *P'* is a clutch for connecting the gear-wheel to the worm. This clutch is normally held in engagement by a lever *Q*, actuated by a spring *Q'*. It is thrown out of engagement by a tripping pawl *Q''*, having a limited sliding movement on the shaft *M*, sliding in the box *M'*, secured to the shaft beside the worm-wheel *R*, Fig. 4.

N'' is a push-rod normally held in its lower position by the spring *O''* and which is actuated by the rock-arm *P''* on the rock-shaft *Q'''*, which is adapted to be rocked by the foot-lever *S''*, extending to the front of the machine.

As the shaft *M* revolves the tripping-pawl *Q''* will strike an extension *T''* of the lever *Q* and disengage the clutch, as shown in dotted lines in Fig. 4. When the operator depresses the lever *S''* and lifts the tripper-pawl *Q''* out of the path of the extension *T''*, the spring *Q'* will throw the clutch into engagement and the shaft *M* will make a complete revolution before the tripper *Q''* strikes the extension *T''* and again disengages the clutch. The worm *P* meshes with a worm-wheel *R*, secured to the shaft *M*, so that when the clutch is engaged the worm will be rotated, and through the worm-wheel *R* the shaft will be rotated, and likewise the cam-wheel *L* and the bevel gear-wheel *e*.

S is a sectional mold, the two sections of which have secured thereto the arms *S'*

which at their inner ends are pivoted upon a common pivot T on the outer end of the lever T', journaled at U in a bracket U' on the frame. The other end of this lever, which is substantially a bell-crank lever T', is connected by a connecting-rod V with a camway V' in the cam-wheel L, the connection being a roller-wrist which is supported upon a lever V''. The mold-sections have also connected to them links W, which have a universal-joint connection with a sliding frame X, which is guided by and supported on the guide-rods X' on the top of the frame. This frame is reciprocated by a connecting-rod Y, having a suitable roller-wrist engaging with a camway Y' in the cam-wheel L. This connecting-rod slides through suitable guides o on the frame X and has a collar r, adapted to engage one of these lugs and with the spring s between the collar and the other lug, so that the frame will be positively actuated in its inward movement and yieldingly in its return movement. This particular form of mechanism for operating the mold-sections is no part 25 of my present invention.

The parts being thus constructed, their operation is as follows: The operator gathers the glass on the blowpipe E in the usual manner and places it in the brackets D and D', 30 with the gathered glass suspended from the lower end. At this time the mold-sections S are in their upper position and open. The operator depressing the lever S'' starts the machine in the manner described. As soon as 35 the cam-wheel L starts to rotate the mold-sections are closed about the glass on the blowpipe. Just before the sections are closed the valve-rod i is actuated by the small cam k', which lifts the valve-rod and opens the 40 valve for an instant, blowing a puff of air into the blank on the end of the blowpipe, expanding it to a size slightly smaller than the interior of the mold, which is then instantly closed about it. The molds being closed 45 about the blank, as shown in Fig. 1, the cam-flange k gradually opens the air-valve, which allows the pressure to enter the article and blow it to the shape of the mold. All the time that the shaft M is rotating the coupler 50 F, together with the blowpipe, will also be rotating through the gear connection described. One of the early movements of the machine is the lowering of the coupler F onto the blowpipe by means of the lever J and the 55 connecting-rod K, where it remains until the blowing is completed. When the blowing is completed, the air-valve will be closed, and the cam will first open the mold-sections and then through the connecting-rod V will rock 60 them in their open position down into the water in the tank B and back again to their

horizontal open position, where they will stop, ready for another operation. The lever J' will be rocked and the coupler F' lifted off, and the blowpipe and the completed article may be removed therewith. 65

In making thin fragile articles, like bulbs for incandescent lamps, if the article is not expanded to nearly the size of the mold before the mold is inclosed about it and the air admitted for blowing it is apt to disfigure or scratch the blank during the blowing operation, and this I obviate by the use of the initial puff of air hereinbefore described.

What I claim as my invention is—

1. In a glass-blowing machine, the combination of an air-conduit leading to the article to be blown, of an air-valve in said conduit, and means for opening and closing the same to admit a limited quantity of air, and means for subsequently opening the valve for blowing purposes, for the purpose described. 75

2. In a glass-blowing machine, the combination of a sectional mold, means for opening and closing the same, an air-conduit leading to the article to be blown, an air-valve in said conduit, means for opening and closing said air-valve before the molds are closed, means for subsequently closing said molds and opening the valve to blow the article. 85

3. In a glass-blowing machine, the combination of the air-conduit into the article to be blown, of means for admitting a limited quantity of air into the article and closing said conduit before the final blowing operation. 95

4. In a glass-blowing machine, the combination of a sectional mold, means for opening and closing the mold, an air-conduit leading to the article to be blown, a valve in said conduit, means for opening and closing said valve before the molds are closed, means for closing the mold thereafter and means for gradually opening the valve subsequent to the closing of the molds. 100

5. In a glass-blowing machine, the combination of a supporting-frame, a reciprocating coupling-nozzle, a support for the blowpipe, means for rotating the coupling-nozzle, a sectional mold, an air-supply leading to the nozzle, a valve therein, a driven shaft, a single cam-wheel thereon and cam-bearings on said wheel for reciprocating said coupling-nozzle, actuating said air-valve, and reciprocating and opening and closing said molds. 110

In testimony whereof I affix my signature in presence of two witnesses.

CORNELIUS J. NOLAN.
